UNITED STATES PATENT OFFICE.

FRANCIS C. HAMILTON, OF SYRACUSE, NEW YORK.

DESIGN FOR A SPOON.

SPECIFICATION forming part of Design No. 23,462, dated July 17, 1894.

Application filed April 20, 1894. Serial No. 508,376. Term of patent 7 years.

To all whom it may concern:

Be it known that I, FRANCIS C. HAMILTON, a citizen of the United States, residing at Syracuse, county of Onondaga, and State of New York, have invented and produced a new and original Design for Spoons and Similar Articles, of which the following is a specification, reference being had to the accompanying drawing, in which I show a front view of my design as applied to a spoon.

The leading feature of my design comprises a handle semi-scroll shaped, and terminating in a circular disk at one end and a spoon at the other.

15 The bowl has the representation of a build-

ing therein, having the general appearance of the one illustrated.

—a— is the handle, —b— the bowl upon which is placed the representation of a building and —c— the opposite termination of the 20 handle.

What I claim is—

The design for spoons and similar articles, substantially as herein described and shown.

In witness whereof I have hereunto set my 25 hand this 12th day of April, 1894.

FRANK. C. HAMILTON.

In presence of—

M. M. BORST,
HOWARD P. DENISON.
